UNITED STATES PATENT OFFICE

2,615,360

KEY HEAD FOR STRINGED MUSICAL INSTRUMENTS

Ferris A. Hawy, Columbus, Ohio

Application June 7, 1949, Serial No. 97,625

2 Claims. (Cl. 84—293)

1

This invention relates to portable string-operated musical instruments, such as the lute, mandolin, banjo or guitar. More particularly, the present invention is concerned with the neck and key-carrying head construction of the lute or other similar instrument, an object of the invention being to provide in a lute or the like a combined neck and key-carrying head, the latter being of integral one-piece construction and of such design as to provide a head of improved strength and adaptability for the performance of its intended purposes.

It is another object of the invention to provide a novel key-carrying head for a lute, or the like, in which the head is provided with a multiplicity of rotatable string-tuning stems or pins, the same being rotated and maintained in adjusted positions of rotation through the use of worm gearing, the metallic parts of the apparatus being unitarily mounted in assembly-providing supports carried in spaced parallel relation by the under side of the head, the top of the head through which the upper ends of the stems or pins project being formed with a guide channel for the reception of the tuning ends of the vibratory strings which are attached to the stems or pins.

For a further understanding of the invention, reference is had to the following description and the accompanying drawing, wherein:

Fig. 1 is a top plan view of the key-carried head of a musical instrument embodying the features of the present invention;

Fig. 2 is a side elevational view thereof, portions of the head being shown in vertical section;

Fig. 3 is a horizontal sectional view taken through the head on the line 3—3 of Fig. 2;

Fig. 4 is a vertical transverse sectional view on the line 4—4 of Fig. 2.

Referring more particularly to the drawing, the numeral 1 designates the vertical neck portion of a stringed musical instrument, such as the lute. The upper end of the neck portion 1 terminates in a laterally extending key-carrying head 2. In accordance with the present invention, the neck 1 and the head 2 are formed from an integral body of wood or other material suitable for its composition. The front 3 of the neck portion is formed to comprise the usual fretted finger board, while the upper part of the head 2 is formed with a string-receiving chamber or pocket 4, having side flanges shown at 5. The flat under face of the head 2 is provided with spaced parallel, longitudinally extending grooves 6 adapted for the reception of metallic channel

2

strips 7, which are fastened as at 8 to the head.

The spaced side ribs 9 of the strips 7 are formed at longitudinally spaced intervals with openings 10 in which are rotatably journaled the shanks 11 of a plurality of tuning keys 12. Between the ribs 9, the shanks 11 are formed with worm threads 13, which mesh with the threads on worm gears 14, the latter being fixed to the lower ends of a plurality of spring-tensioning stems or pins 15. The latter are rotatably mounted in bearing openings 16 provided therefor in the head 2 and in registering portions of the strips 9. The upper ends of the stems or pins project into the chamber or pocket 4 of the head, and are adapted to have wound thereabout the ends of a plurality of vibrating strings 17 of the musical instrument, the strings, as shown in Fig. 1, extending through the pocket or channel and downwardly over the face of the finger board 3 in appropriately spaced relationship.

My improved turning head is characterized by the fact that there is no back lash between the worm gears and the worms, nor is there any undue binding in the gearing assemblies as a whole.

Also, by the employment of the channel strips, the metallic parts of the head may be applied to the head proper as composite units, a feature which facilitates manufacture and insures proper registration and maintenance of such registration between relatively movable parts.

It will be understood, however, that the invention is not to be restricted to the exact mechanical details set forth, since the same may be modified within the scope of the appended claims.

35 I claim:

1. In a lute, a neck portion terminating at one end in a laterally extending integral key-carrying head, the upper side of the head being formed with a recessed string-receiving chamber bounded by vertical marginal walls, string-winding and tuning stems extending perpendicularly through said head and terminating at one end within the confines of the marginal walls of said chamber, the under side of said head being provided with 40 a pair of parallel longitudinally extending straight grooves, stationary metallic members positioned in said grooves, rotatable key members carried by said metallic members, and worm gearing actuated by said key members for imparting controlled rotation to said string-winding stems.

2. In a lute, a neck portion terminating at one end in an integral sharply angularly related key-carrying head, said head being recessed at the upper side thereof and formed with a string-re-

ceiving chamber bounded by vertical marginal walls, and formed on the under side thereof with longitudinally extending straight grooves; a plurality of relatively spaced rotatable string-receiving and tuning stems extending perpendicularly through said head and terminating at one end below the plane of the marginal walls bounding said chamber; a plurality of metallic channel members stationarily carried in the grooves formed in the under side of said head; a plurality of manually operable keys rotatably journaled in said channel members and extending laterally outwardly on either side of said head; and worm gearing carried within said channel members and actuated by said keys for imparting controlled rotation to said stems.
